UNITED STATES PATENT OFFICE

LOUIS H. PERLMAN, OF NEW YORK, N. Y.

DEMOUNTABLE RIM.

1,267,112.

Specification of Letters Patent.

Patented May 21, 1918.

Application filed January 10, 1917. Serial No. 141,638.

To all whom it may concern:

Be it known that I, Louis H. PERLMAN, a citizen of the United States, residing at New York, in the county of New York and State of New York, have invented certain new and useful Improvements in Demountable Rims; and I do hereby declare the following to be a full, clear, and exact description of the invention, such as will enable others skilled in the art to which it appertains to make and use the same.

This invention relates to improvements in demountable rims of the cross-cut type, and more particularly to means thereon for receiving and sustaining a rim manipulating tool.

The object in view is the provision of means not in any way interfering with the normal use of a demountable rim for easily, quickly and efficiently detachably receiving a rim manipulating tool.

With this and further objects in view as will in part hereinafter become apparent and in part be stated, the invention comprises certain novel constructions, combinations and arrangements of parts as subsequently specified and claimed.

In the accompanying drawings,—

Figure 1 is a perspective view of a rim embodying the features of the present invention.

Fig. 2 is a cross section therethrough taken on the plane indicated by line 2—2 of Fig. 3.

Fig. 3 is a plan view of a fragment of the rim at the place of the tool receiving means.

Fig. 4 is a perspective view of a rim manipulating tool, shown on a reduced scale.

Fig. 5 is a fragmentary view in elevation of the fulcrum post of the tool, the scale being actual size of the average tool.

Fig. 6 is a cross section taken on the plane indicated by line 6—6 of Fig. 1.

Fig. 7 is a view similar to Fig. 3 of a modified embodiment of the invention.

Fig. 8 is a longitudinal section taken on the plane indicated by line 8—8 of Fig. 7.

Fig. 9 is a transverse sectional perspective taken on the plane indicated by line 9—9 of Fig. 7.

Fig. 10 is a view similar to Fig. 3 of another modified embodiment.

Referring to the drawing by numerals, 1 indicates a demountable rim of the cross-cut type having the latch plate 2 fixed to one end of the rim and lapping a portion of the other end and provided with a hook 3 ex-

tending through an aperture 4 in the second-mentioned end of the rim for locking the rim ends together. For facility of designation, that end of the rim 1 provided with the aperture 4 will be called the apertured end of the rim, and the other end of the rim will be mentioned as the latch-carrying end.

The latch-carrying end portion of rim 1 is provided with the usual valve stem hole surrounded by a driver 5 of the well known type which is adapted to enter a corresponding recess in the felly band of the wheel (not shown) for transmitting driving stresses and preventing rotary shifting of the rim on the wheel during use.

Between the valve stem hole and the latch 2, the rim 1 is provided with a post-receiving member adapted for detachably but rigidly anchoring a post in a manner enabling the post to be easily and quickly detached, whereby a post forming part of a rim manipulating tool may be connected with the rim 1 at the latch-carrying end thereof. The said post-receiving member consists of a plate 6 welded, riveted or otherwise appropriately fixed to the inner surface of the rim and having an undercut slot 7 formed longitudinally therein arranged with its median line coincident with the median line of the rim. The undercut of the slot 7 provides an overhanging flange 8 throughout the greater part of the length of the slot but at that end nearer the valve stem hole the slot is formed with a curved enlargement 7' which opens through the flange 8.

Rim 1 is adapted for being manipulated for the application or removal of a rim by the use of a tool similar to that disclosed and described in my co-pending application filed December 4, 1916, and designated by Serial No. 135,071, but differing slightly therefrom in the detail form of the engaging portion of the fulcrum post. To render clear the form of tool referred to, and to thus facilitate an understanding of the utility of the hereinafter claimed features of rim 1, the said tool is disclosed in detail in Fig. 4 wherein is shown the post 9 having at its free end an annular flange 10. An annular guard 14 is spaced above flange 10 and preferably formed integral with post 9. In practice, guard 14, engages the outer surface of the material beneath which, flange 10 is positioned, and thereby the post is firmly held against play. The post 9 is bifurcated and between the arms of the bi-

furcation is fulcrumed a lever 11 which pivotally carries a pair of links 12 having terminal hook portions adapted to enter apertures 13 in the apertured end of rim 1. The preferred manner of manipulating this tool is fully set forth in my above mentioned copending application, and consists in anchoring the post 9 to the latch carrying end of the rim, inserting the hooks of links 12 into apertures 13, then swinging the lever 11 for causing the apertured end of rim 1 to move inward away from the hook 3 and over toward the anchored post, the lever 11 swinging past its fulcrum and moving the pivots of links 12 below the plane of the pivotal connection between the lever and its fulcrum post. In this collapsed condition of the rim a tire may be removed and another tire applied readily and then the rim is restored to its normal circular condition by a reverse movement of lever 11.

The means for anchoring the fulcrum post in said co-pending application, however, differs from that disclosed herein. The said anchoring means in the present structure consists of the plate 6 coöperating with the flange 10 and guard 14. The method of operation of the tool and the manipulation of the rim are otherwise identical with that of the said co-pending application. In the present improved structure, the tool is applied by inserting the flange 10 through the enlarged end portion of slot 7, the enlargement 7' being sufficient to accommodate the introduction of the flange 10 as clearly indicated by the dotted lines in Fig. 3. The post 9, after the flange 10 has been introduced through the enlarged end of slot 7 is moved laterally for positioning the flange 10 beneath the flange 8 and then the post 9 is slid along the slot 7 until it arrives at that terminus opposite the enlarged end. In this position a maximum amount of flange 8 is overhung by guard 14, and a maximum amount of the flange 10 is overhung by flange 8. The parts are proportioned for having the undercut space of slot 7 snugly receive the flange 10, and for having the space between guard 14 and flange 9 snugly accommodate flange 8, so that the flange 8 effectively prevents any wobbling of the post 9 during operation. When the post is in this position and the links 12 have been caused to engage the apertures 13 the tool is in position for manipulating the rim as above described. After the interchange of tires has been accomplished and the tool restored to the initial position, the links 12 are released from their engagement with the apertured end of the rim, then the post 9 is slid back to a position for bringing the flange 10 into register with the enlarged end of slot 7. Thereupon the post is lifted from the slot and the rim is ready for use.

It is obvious, of course, that instead of

utilizing a separate plate 6 the material of the rim 1 may be stamped to form the tool receiving slot provided in plate 6, but in such event the depression in the rim would necessarily be covered by a plate at the exterior surface of the rim for protecting the inner tube of a tire carried by the rim. Such a structure is seen in Figs. 7, 8 and 9 wherein the material of the base 1' of the rim is stamped and offset inward forming longitudinally extending flanges 8', 8', and transverse flanges 8'', 8'', the flanges 8' and 8'' being blended into each other in the course of formation, and the said flanges being shaped to produce an undercut slot 7' similar in form and function to the slot 7, and having the enlargement 7'' similar in form and function to the enlargement 7'. The opening through the base 1' which would otherwise result from the stamping of the flanges 8' and 8'' and the cutting away of material for producing slot 7' is closed by a cover plate 6' whose side and end edges are formed with inwardly extending flanges 6'' shaped to snugly fit the curved inner faces of the flanges 8' and 8''. The inner faces of the flanges 6' are preferably straight so that the undercut portions of the slot 7' are bound by flat right angular surfaces. The operation of the tool in connection with the structure seen in Figs. 7, 8 and 9 is the same as that above described. It is apparent, of course, that the plate 6' may be fixed to the base 1' in any appropriate manner, such as by welding or riveting.

In Fig. 10 is shown a further embodiment of the invention wherein the plate 6*, corresponding in function to plate 6, is fixed to the inner face of the base 1* of the rim. The plate 6* is formed with a slot 7* which has one end open at 7* for enabling the introduction of the flange 10 of the tool with a lateral sliding movement in lieu of the introduction endwise as is shown in applying the tool through the enlargement 7'. In the operation of the structure seen in Fig. 10, the manipulation of the tool is the same as that above described and its application to the plate consists merely in sliding the tool across the rim through the entering end 7* of the slot 7* and then along the slot in a direction toward the locking hook 3*. In this position the tool is manipulated as above described and after the operation is completed the post 9 is slid out of the slot 7* by a reverse movement to that of its introduction.

What I claim is:—

1. A cross-cut demountable rim having an undercut slot adapted to receive a portion of a rim manipulating tool, the undercut of the slot being adapted to be engaged by a portion of the tool, and the slot having an enlargement at one place of a size adapted to

permit the passage of that portion of the tool designed to engage the undercut portion of the slot.

2. A cross-cut demountable rim having an undercut slot adapted to receive a portion of a rim manipulating tool, and to have a portion of the tool engage beneath the undercut of the slot, a portion of the slot being enlarged and shaped to correspond with the size and shape of the undercut engaging portion of the tool for permitting said portion to pass to and from a position in engagement with the slot.

3. A cross-cut demountable rim having an undercut slot adapted to receive a portion of a rim manipulating tool, the slot being formed in material stamped from the rim.

4. A cross-cut demountable rim having an undercut slot adapted to receive a portion

of a rim manipulating tool and to have a portion of the tool engage beneath the undercut of the slot, the slot being formed with an opening for admitting the passage of the underlying portion of the tool.

5. A cross-cut demountable rim having an undercut slot adapted to receive a portion of a rim manipulating tool and to have a portion of the tool engage beneath the undercut of the slot, the slot being formed with an end opened for permitting the ready passage of the underlying portion of the tool to and from an underlying position.

In testimony whereof I affix my signature in presence of two witnesses.

LOUIS H. PERLMAN.
